UNITED STATES PATENT OFFICE.

FELIKSAS KIEKUTIS, OF LAWRENCE, MASSACHUSETTS.

POTATO GRATER.

Application filed March 9, 1921. Serial No. 450,809.

To all whom it may concern:

Be it known that I, FELIKSAS KIEKUTIS, a citizen of Lithuania, residing at Lawrence, county of Essex, and State of Massachusetts, 5 have invented certain new and useful Improvements in Potato Graters, of which the following is a specification.

This invention relates to improvements in vegetable graters, particularly potato 10 graters.

It is the principal object of the invention to provide a grater of improved construction and combination of parts in which the potatoes are fed to the grater under 15 pressure and thereafter quickly and easily removed.

A further object of the invention is the provision of a grater which contains storage bins for the potatoes and which allows a 20 locking of the pressure means.

Other objects and advantages of my invention will become more fully apparent as the description thereof proceeds and will 25 then be specifically pointed out in the appended claim.

In the accompanying drawings I have disclosed a preferred form of my invention as illustrating the same by way of example.

In these drawings,

30 Figure 1 is an end elevation of a grater constructed according to the present invention.

Figure 2 is a side elevation of the same.

35 Figure 3 is a vertical section through part of a grater on an enlarged scale, the section being taken on line 3—3 of Figure 2, and

Figure 4 is an inner detail view of the fastening spider for the grater sleeve.

40 The grater, as illustrated, comprises a box 10 of any suitable material having a plurality of compartments, for instance a lower drawer 11 having at its front a handle or grip 12, and two upper compartments 13 and 14 serving as storage bins for the potatoes to be grated. These compartments are closed on top by covers 15 and 16 respectively which are hinged to the box cover as at 17 and 18, and are provided at their front 45 edges with metal angle irons or bands 19 and 20 respectively, the lower ends of which are perforated to allow the passage of pins 21 for keeping the covers locked.

The central compartment 22 is extended 50 towards one side to form a chamber 23 closed

by a door 24, which is fastened in closed position by an angle iron or band 25 held in position by the engagement of its end perforation with a pin 26.

In the central compartment 22 a grater 27 of circular cross-section is horizontally disposed, so that its rear end, provided with a band 28 having openings 29 adapted to engage pins 30 of a spider 31, is secured to said spider by means of a so-called bayonet 65 lock.

This spider 31 is rotatably secured to a shaft 32 extending through the outer, somewhat extended wall 33 of the box 10 and carrying at its outer end a gear 34 in mesh 70 with a gear 35 on a stub shaft 36 journaled in the extension wall 33 and in mesh with a large gear 37, adapted to be operated by a crank 38, said gear 37 is secured to a shaft 39 journaled in the box 10. 75

The forward end of the grater sleeve 27 is supported by a semi-circular band 40 pivotally secured at its upper ends as at 41 to the inner wall of the box.

The potatoes to be grated are fed to the 80 grater 27 through a feed box 42 and pressed against the grater 27 by means of a head 43 sliding vertically in guides 44 at the inner walls of an upper extension 45 of the box. 85

This head 43 is moved up and down by means of a pair of bars 46 secured with their lower ends to said head and extended through a top plate 47 of the extension 45, the upper ends of which are united by a 90 cross-piece or handle 48 provided with a ring 49.

Between the under face of the plate 47 and the upper face of the head spiral springs 50 are wound around the bars 46. The bars 95 are provided with notches in their inner faces for the reception of the ends of a locking latch 51 pivoted to the top of plate 47 as at 52 so that the head can be locked in its elevated position for allowing a feeding of the potatoes to the box 42. Handles or rings 53 are provided at the end walls of the box for allowing a convenient transportation of the same. 100

It will be clear that changes may be made 105 in the general arrangement and construction of the minor details of my grater without deviating from the scope and spirit thereof.

The operation of the device will be quite 110

clear from the above description and it is therefore believed that the same need not be further described in detail.

Having thus described my invention, what I claim as new and desire to secure by Letters Patent of the United States is—

In a potato grater of the character described, comprising a box having an upper extension, guides at the inner walls of said extension, a head sliding vertically in said guides, a pair of bars secured to said head and extended through the top plate of said extension, a cross piece uniting the upper

end of said bars, spiral springs coiled around said bars between said head and the under face of said cross piece, said bars provided with notches along said cross piece, and a locking latch on top of said cross piece adapted to engage said notches for locking said head in its uppermost position against the action of said springs for allowing a feeding of the material to be grated to the grater.

In testimony whereof I have affixed my signature.

FELIKSAS KIEKUTIS.
